ORGAN BENCH

Hubert S. Shearin and Charles Riley, Cincinnati, Ohio, assignors to Manual Arts Furniture Company, Cincinnati, Ohio

Filed Feb. 28, 1973, Ser. No. 336,513

Term of patent 14 years

Int. Cl. D6—01

U.S. Cl. D6—32

FIG. 1 is a perspective view of an organ bench embodying the new design.

FIG. 2 is a top plan view thereof.

FIG. 3 is a side elevational view of the organ bench, the opposite sides being the same.

FIG. 4 is an end elevational view thereof, the opposite ends being the same.

We claim:

The ornamental design for an organ bench, as shown and described.
